(57) **CLAIM**

I claim, the ornamental design for an earthquake-resistant deck insert, as shown and described.

DESCRIPTION

FIG. 1 is a perspective view of an earthquake-resistant deck insert showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an exploded view of the earthquake-resistant deck insert.

1 Claim, 8 Drawing Sheets(56)
